TIE AND SHIRT GARTER

Filed May 8, 1939

FIG. 8

FIG. 6

FRANCIS E. BERTLING

Inventor

By *Herbert E. Smith*

Attorney

UNITED STATES PATENT OFFICE

2,210,275

TIE AND SHIRT GARTER

Francis E. Bertling, Spokane, Wash.

Application May 8, 1939, Serial No. 272,356

4 Claims. (Cl. 24—73)

My present invention relates to a tie and shirt garter to be worn as an article of jewelry to ornament a necktie and to retain a tie and shirt in a taut manner across the bosom of the wearer.

5 An object of the invention is to provide an article of jewelry which is attractive in appearance when worn and useful to retain a tie to a shirt of the wearer.

Another object of the invention resides in the 10 provision of an article of jewelry to be used in connection with the tie and shirt which may be easily and positively attached in place.

15 A further object of the invention has been to provide an article of jewelry particularly designed for display with relation to a four-in-hand tie embodying a plurality of clasps whereby the tie and shirt may be independently gripped, and having means depending therefrom for engagement upon a lower portion of clothing for holding 20 the tie and shirt tautly and smoothly across the bosom of the wearer.

25 A still further object of the invention resides in the combination with shirt and tie grip means of an elastic garter which may be secured to a lower portion of clothing in a simple and positive manner.

Still another object of the invention has been 30 the provision of an article for securely gripping the shirt and tie of a wearer and anchoring them to a lower garment, which article is simple of construction and operation.

35 Other objects and advantages of the invention will be apparent during the course of the following description, where the construction and operation of the device and the arrangement of parts is more fully set forth and defined in the subjoined claims.

In the accompanying drawing forming a part 40 of this specification, and in which like numerals indicate like parts throughout the same,

Figure 1 is a front elevational view of the invention shown as applied to wearing apparel with parts in dotted lines for convenience of illustration,

45 Figure 2 is a top view of the invention as it would appear unattached from any wearing apparel.

Figure 3 is a front view of the invention illustrating the general arrangement of parts,

50 Figure 4 is an edge view of the central jaw of the invention,

Figure 5 is a face view of the jaw of Figure 4,

55 Figure 6 is a longitudinal sectional view through the face jaw of the invention,

Figure 7 is a vertical sectional view taken on line 7—7 of Figure 3, and

Figure 8 illustrates a modified form of one of the jaws of the invention.

In the drawing, wherein for the purpose of illustration of my invention is shown a preferred embodiment and a modified form of my invention, the numeral 10 designates a portion of the front of a shirt having a collar 11. A four-in-hand tie is indicated by the numeral 12 and is knotted 10 at 13 in the usual manner. An upper portion of a pair of trousers is designated 14, and a belt 15 is also shown.

Referring now to Figures 2 and 3, where the device of my invention is shown as a whole, the 15 numerals 16 and 17 designate front and rear pivoted spring-pressed jaws of the clasp. These jaws are preferably formed with an interior channel, the edges 20 of which are provided with segmental tooth portions 21. Ears 22 stand somewhat above the general contour of the edges 20 and are provided with pivot holes 23.

A central jaw 18, as may best be seen in Figures 4 and 5, comprises a strip or blade 19 of metal or other suitable material that is flat 25 throughout its length and of a relatively great stiffness. A pair of bosses 24—24 are shown struck up from the rear face of the blade. A loop 25 is formed in one edge of the blade 19 for a purpose later to be described. At one end of the 30 blade I attach a collar or bushing 26 through which passes the pivot pin 27, and a notch 28 is cut in the blade for the accommodation of a spiral spring 29 having ends 30 and 31, which extend outward and away from the blade 19.

35 A length of elastic material 32 is passed through the loop 25 and stitched securely in place at 33. A second spring-pressed clamp or clasp 34 is supported from the opposite end of the elastic 32 by means of the loop on one of its jaws.

40 In certain cases I use the jaw or blade 36, which is similar to the blade 19 in most respects except that it is provided with a button engaging loop 37 extending from one edge of the blade in opposition to the loop 25. Also the blade has an 45 extension 38 against which is seated the end 30 of the spring 29.

The jaw 16 is illustrated as having an embossed decorative face, and of course it is understood that the decoration utilized here may be varied 50 without altering the principles of the invention.

The jaws 16 and 17 are pivotally mounted upon the collar 26 by means of the pin 27, and the spring ends 30 and 31 are seated within the channels 19—19 so as to urge the segmentally 55

toothed ends of the jaws downward against the jaw 18. By gripping the opposite ends of the jaws between the thumb and forefinger one can easily compress the springs and spread the jaws open away from jaw 18.

To attach the device to his clothes a wearer merely opens the jaws of the clasp 34 and grips it to the upper edge of his trousers or to the belt if that is deemed desirable. Then, by gripping the jaw ends of the jaws 16 and 17, the double clasp may be attached to the shirt, which passes between jaw 17 and jaw or blade 18, and to the tie by inserting the ends thereof between jaw 16 and the blade 18. The bosses 24-24 on the blade serve to make more positive the grip secured upon the shirt when the jaws are released thereon.

In view of the fact that the trousers are reasonably heavy or fit snugly so as not to be able to be raised, they form an excellent anchor for the device. In attaching the device the shirt is drawn smoothly across the bosom and the clasps attached so that the elastic strip is taut, and preferably under some tension. Thus, when the wearer sits down so that the distance between the top of his trousers and his collar shortens, the elastic webbing will contract and tend to draw the shirt and tie smoothly down on the chest.

30 The jaw 17 may be eliminated by the use of the alternative or modified jaw 36 to which, of course, I attach the jaw 16 in the aforescribed manner. This is possible because the shirt may be engaged at a convenient button by the loop 37 passing thereover to anchor the device to the shirt.

It is contemplated that in certain instances the clamp or clasp 34 may be eliminated and a button engaging loop similar to 37 may be attached to the end of the elastic strip 32 for anchoring the device to a trouser button rather than by clamping the trousers proper.

Also, the elastic strip may be provided with a take-up device for adjusting its length to meet varying conditions.

It is to be understood that the form of the invention, herewith shown and described, is to be taken as a preferred example of the same, and that various changes in the shape, size and 50 general arrangement of parts may be resorted to without departing from the spirit of my invention, or the scope of the subjoined claims.

Having thus fully described my invention, what I claim as new and desire to secure by Letters Patent is:

55 1. A holder for ties and shirts comprising anchoring means for engagement with a lower garment of the wearer, elastic means secured to

said anchoring means and extending upwardly therefrom, and a clasp comprising a central jaw having an opening therethrough adjacent one end, a trunnion and a pivot pin supported therein on the end of the jaw adjacent said opening, 5 a loop along one side of the central jaw, a pair of channeled jaws pivotally mounted upon said pin on opposite sides of the central jaw, a helical twist spring encircling said trunnion and passing through said opening and having a spring extension finger on each end for applying tension to the under side of the channeled jaws.

2. A holder for ties and shirts comprising anchoring means for engagement with a lower garment of the wearer, elastic means secured to 15 said anchoring means and extending upwardly therefrom, and a clasp comprising a central jaw having an opening therethrough adjacent one end and grip means on one face, a trunnion and a pivot pin supported therein on the end of the 20 jaw adjacent said opening, a loop along one side of the central jaw, a pair of channeled jaws pivotally mounted upon said pin on opposite sides of the central jaw, one of said jaws having a segmental toothed portion cooperating with said 25 grip means on the central jaw, a helical twist spring encircling said trunnion and passing through said opening and having a spring extension finger on each end for applying tension to the under side of the channeled jaws. 30

3. A holder for ties and shirts comprising anchoring means for engagement with a lower garment of the wearer, elastic means secured to said anchoring means and extending upwardly therefrom, and a clasp comprising a central jaw having an opening therethrough adjacent one end and spaced bosses on one face, a trunnion and a pivot pin supported therein on the end of the 35 jaw adjacent said opening, a loop along one side of the central jaw, a pair of channeled jaws pivotally mounted upon said pin on opposite sides of the central jaw, one of said jaws having a segmental toothed portion cooperating with said 40 spaced bosses on the central jaw, a helical twist spring encircling said trunnion and passing through said opening and having a spring extension finger on each end for applying tension to the under side of the channeled jaws. 45

4. A clasp for ties and shirts comprising a central jaw having a trunnion and a pivot pin 50 therein on one end and an opening through said jaw adjacent said trunnion, a pair of channeled jaws pivotally mounted upon said pin, a helical twist spring encircling said trunnion and mounted in said opening and having a spring extension finger on each end engaging the under side of one 55 of the channeled jaws.

FRANCIS E. BERTLING.
